UNITED STATES PATENT OFFICE.

JOSEPH BULOVA, OF NEW YORK, N. Y.

SLEEVE-BUTTON.

SPECIFICATION forming part of Letters Patent No. 364,212, dated June 7, 1887.

Application filed April 9, 1887. Serial No. 234,287. (No model.)

To all whom it may concern:

Be it known that I, JOSEPH BULOVA, a citizen of the United States, residing at New York, county and State of New York, have invented 5 a new and Improved Sleeve-Button, of which the following is a specification.

This invention relates to a sleeve-button of the kind in which the shoe may be folded over to pass through the holes in the cuff. The 10 button is so constructed that the pin which connects the shoe to the shank may be pushed out of its seat if the parts are to be disconnected, but is prevented from spontaneous displacement by means of a projecting shoulder 15 or rim.

The invention consists in the various features of improvement, hereinafter more fully pointed out.

In the accompanying drawings, Figure 1 is 20 a top view of my improved sleeve-button, showing the shoe folded. Fig. 2 is a section on line *x* *x*, Fig. 1, but showing the shoe not folded. Fig. 3 is a section on line *y* *y*, Fig. 1, also showing the shoe not folded. Fig. 4 is a 25 vertical central section of a modification.

With particular reference to Figs. 1 to 3 the letter *a* represents the head of a sleeve-button rigidly connected to the shank *b*, that has a turned-over end or cam, *c*. This cam *c* is 30 perforated for the reception of pivot *d*, which connects the shank to the shoe. The shoe is composed of a lower plate, *e*, which is bent upwardly at its edge to inclose the edge of an upwardly-bulged or convex plate, *f*, as shown. 35 In this way an upwardly-projecting rim or bead, *g*, is formed around the plate *f*. The plate *f* is cut out or slotted at its center to accommodate the shank *b*, and it is also perforated in a horizontal direction, as shown, for 40 the accommodation of the pivot *d*, the perforation being open from end to end. It will

be seen that by the use of a convex plate *f* that receives the pivot-pin I can dispense with the ordinary lugs or bearing plates used to receive the ends of such pivot. 45

The bead *g* projects somewhat above a part of the perforation in the plate *f*, Fig. 2, and consequently above the lower edge of the pivot, and thus the pivot is prevented from becoming automatically displaced; but if it is desired 50 to remove the pivot, which must sometimes be done in the manufacture of the goods, the pivot is pushed toward the rim *g*, and is then slightly raised to clear such rim, after which the pin may be readily withdrawn. To facilitate such withdrawal of the pivot, its ends should be made somewhat tapering or pointed. 55

i represents the spring within the shoe, that bears against the cam *c*.

In Fig. 4 the perforation within the plate *f* 60 is provided with two shoulders, *h*, against which the pivot abuts when the parts are in their normal position, and which prevent the automatic displacement of the pivot; but when the parts are to be disconnected a slight pressure upon the head *a* will push the pivot downward (against action of spring *i*) to clear the shoulders, after which the pivot may be readily withdrawn. 65

What I claim is— 70

The combination, in a sleeve-button having head *a* and shank *b*, of a pivot, *d*, passing through such shank, and a shoe provided with a perforation open from end to end, adapted to receive the pivot, and provided 75 with a raised rim or shoulder that extends partly over such perforation, substantially as specified.

JOSEPH BULOVA.
